UNITED STATES PATENT OFFICE.

DAVID M. SCHEFFER, OF NEW CASTLE, INDIANA, ASSIGNOR TO HAUSMANN,
McCOMB & DUNN, OF CHICAGO, ILLINOIS.

VETERINARY FILE-HOLDER.

SPECIFICATION forming part of Letters Patent No. 403,145, dated May 14, 1889.

Application filed July 26, 1888. Serial No. 281,130. (No model.)

To all whom it may concern:

Be it known that I, DAVID M. SCHEFFER, a citizen of the United States, and a resident of New Castle, in the county of Henry and State 5 of Indiana, have invented certain new and useful Improvements in File-Holders, of which the following is a specification.

This invention relates to improvements in file-holders especially designed for the use of 10 veterinary surgeons, in which heretofore the file has been secured in position by set-screws passing through the holder and entering the body of the file. In this old form of device, however, the edges of the file were left un- 15 protected and projected from the handle in such manner as to constantly endanger the laceration of the gums of the animal being operated upon, frequently rendering the mouth so sore as to prevent the animal from eating 20 for some time, which, however, is by no means the most serious damage that might result from such laceration.

The prime object of this invention is to avoid the danger of lacerating or otherwise 25 injuring the mouth or gums of the animal by providing a holder for the file of such a character that the edges thereof will be opposed to and shielded by the rounded edges of the holder upon all sides, whereby neither the 30 edges nor the operating-faces of the file can be brought into contact with the gums or mouth of the animal.

Another object is to have the file detachably secured in the holder by friction only, 35 whereby it may be readily reversed or removed and the necessity for perforating or otherwise marring the same dispensed with.

A further object is to have a jointed or 40 double holder provided with reverse files and tongue-shields, thus combining a right and left tool in one instrument, whereby the operator may not only operate upon either side of either jaw with one and the same instrument, but he is also enabled to ascertain by 45 observing the unused part of the instrument during the operation the exact angle or position of the operating file relative to the teeth.

I attain these objects by the devices illustrated in the accompanying drawings, in 50 which—

Figure 1 represents a perspective view of

a file and holder embodying my invention; Fig. 2, a transverse section on the line 2 2 of Fig. 1; and Fig. 3, a similar section on the line 3 3 of Fig. 1, showing the manner of holding 55 the files rigidly in position.

Similar letters of reference indicate the same parts in the several figures of the drawings.

Referring by letter to the accompanying 60 drawings, A B represent the two parts of the file handle or holder, connected together by a rule-joint, C, which permits the folding of the file for convenience of transportation, and also enables the bringing of the handles into 65 alignment with each other, in which position they will be locked by the shoulders D of said joint coming into engagement, so that in operation either section of the holder may be held in the hand. The outer free ends of the 70 sections are formed into a U-shaped socket, E, by having the end F extend backwardly, so as to oppose a lug or boss, G, projecting laterally from the main portion of the handle, with which engages a screw, H, working freely 75 through the end of the part F, so as to cause the said part F to move laterally. In the U-shaped portion of the handles is socketed a file, I, held between the part F and the opposing body of the handle by friction only, 80 the spring of the metal composing the part F being utilized to release the file whenever the screw H is manipulated.

On the inner or opposing faces of the holder the file lies flush with or slightly below the 85 edges of the holder, which latter are rounded off at the front and rear and upon one side, while upon the opposite side and projecting from the body of the handle beyond the face of the file is a tongue - shield, J, extending 90 substantially the entire length of the file, rounded upon the edges thereof, and preferably projecting about a half inch above the operating-face of the file. This shield, in the practical use of the file, is designed 95 to lie on the inside of the teeth, so as to prevent the laceration of the tongue by its being inserted between the file and the teeth during the operation of filing, and this will be the case whether the upper or lower jaw 100 of the animal is being operated upon, because each section of the handle is provided with a

shield upon the same side, but reversed as to the file; and hence one file will be employed while operating upon the left-hand side of the upper or right-hand side of the lower jaw, 5 and vice versa. All the other edges of the holder are also rounded, so that in operation, if brought into contact with the cheek or gums of the animal, the parts will not be lacerated, as has been the case in the prior construction, in which the edges of the file, particularly the front and rear edges thereof, have projected above the holder, so that the sharp edges thereof would lacerate the cheek and gums of the animal at almost every stroke 15 of the file.

The peculiar method of holding the file in position, as herein shown and described, is also of advantage, not only because it reduces the weight of the file as a whole, but also because 20 it obviates the necessity for having a screw-threaded hole in the file, from which the screw must be removed every time it is desired to reverse or change the file, and a file so constructed is far more convenient for manipulation than the devices heretofore in use, because of the greater facility with which the file may be removed from or reversed in the 25 holder.

Another advantage of employing a jointed 30 or double holder, either section of which constitutes a handle when the file on the other is in operation, is that in such an instrument is embodied the two instruments heretofore necessary for performing its functions, a right 35 and a left, or two distinct and separate tools, reversed as to each other for operating on the different sides of the upper and lower jaws, besides which the operator can readily ascertain the exact angle at which the file is work-

ing on the teeth by simply observing the angle of the section held in his hand, while in the old and single form of instruments the round handle gives no indication whatever of the position of the file in the animal's mouth, and as a consequence the successful performance 45 of the operation is rendered extremely difficult and fatiguing both to the animal and operator.

Having described my invention, what I claim, and desire to secure by Letters Patent, 50 is—

1. The combination, with a file, of a holder provided with a socket for the reception of said file, and a spring clamping device for locking the file in position, whereby friction 55 alone operates to hold the file, substantially as described.

2. The combination, with a file, of a holder provided with a socket for the reception and of substantially the depth of said file, a 60 spring-arm on said holder, and a screw working through said arm and engaging the body of said holder, substantially as described.

3. The jointed holder composed of sections having a hinge-connection therebetween, in 65 combination with files mounted in each of said sections, substantially as described.

4. The jointed holder composed of sections hinged together, each of which has a file-socket therein, and tongue-shields at the reverse sides of said sockets, in combination with files fitting into each of said sockets and spring clamping devices for locking said files in position, substantially as described. 70
